UNITED STATES PATENT OFFICE.

FRANCIS A. J. FITZGERALD, OF NIAGARA FALLS, NEW YORK, ASSIGNOR TO HARPER ELECTRIC FURNACE CORPORATION, A CORPORATION OF NEW YORK.

ELECTRIC FURNACE.

Application filed June 1, 1925. Serial No. 33,924.

This invention relates to a furnace and particularly to the type of furnace wherein material being heated is located at some distance from the source of heat and is heated 5 from such source by conduction or conduction and radiation. The primary object of my invention is to provide an improved furnace structure whereby a considerable 10 quantity of material may be quickly raised to a temperature which is uniform throughout its mass. Other objects of my invention will appear from the following description, taken in connection with the accompanying drawing which represents diagrammatically, partly in vertical transverse section and partly in elevation, an electrically 15 heated tunnel kiln embodying one form of my invention.

Referring to the drawing, 1 represents 20 the outer casing of the furnace, 2 the tunnel through which is passed the car or cars 3 carrying the material 5 to be subjected to heat-treatment. The resistor 4, heated by the passage of an electric current, radiates 25 its heat to the septum 6 which forms the cover or roof of the tunnel, and this septum in turn radiates heat to the material 5 carried through the tunnel on cars 3.

As furnaces of this type are ordinarily 30 constructed, the top of the material carried on a car will heat more rapidly than its lower portions, for the reason that the top is much nearer to the source of heat-supply. To overcome this disadvantage, I form a 35 lining 7 for the upper portion of the tunnel and the roof of the tunnel of high heat-conducting refractory material, so that heat absorbed from the resistor by the tunnel roof will be conducted down the sides of the 40 tunnel 2 through the side lining 7 and will be radiated laterally to the material carried by the truck 3. As a material for lining the tunnel and forming the roof 6, I preferably

employ re-crystallized silicon carbide, the inner lining of the tunnel being preferably 45 formed of bricks or tiles of that material, and I also provide baffles 8 which extend laterally into recessed portions formed in the truck body and so provide means whereby heat may be radiated upwardly to the 50 material being heated.

While I have shown my invention as applicable to tunnel kilns, it is obvious that it is also applicable to muffle furnaces or any other furnace of this general type. 55

I claim:

1. In an electric furnace the combination with an outer casing having a resistor chamber confined to its upper portion, of a resistor extending through said chamber and radiating heat downward, article conveying means at the lower portion of the space within said casing, and a heat conducting structure to distribute the heat supply to the articles on said conveying means comprising side members of heat conducting material extending downward along the sides of the casing to a point below the articles and a septum member of heat conducting material between the articles and said resistor chamber. 65

2. In an electric furnace the combination with an outer casing having a resistor chamber confined to its upper portion, of a resistor extending through said chamber and radiating heat downward, article conveying means at the lower portion of the space within said casing, and a heat conducting structure to distribute the heat supply to the articles on said conveying means comprising side members of silicon carbide extending downward along the sides of the casing to a point below the articles and a septum member of silicon carbide between the articles and said resistor chamber. 75 80

FRANCIS A. J. FITZGERALD.
